ASSEMBLING MEANS FOR TYPOGRAPHICAL MACHINES

Herman R. Freund, Brooklyn, N. Y., assignor to Intertype Corporation, Brooklyn, N. Y., a corporation of New York

Application June 12, 1933, Serial No. 675,473
Renewed October 12, 1934

12 Claims. (Cl. 199—19)

The present invention relates to improvements in typographical machines and more especially to those of the class adapted to contain a plurality of matrix magazines arranged in superposed relation and provided with respective sets of escapements for controlling the delivery of matrices therefrom for assembling in lines from which type bars or slugs may be cast, the sets of matrix controlling escapements for the respective magazines being each provided with a set of actuating devices, and the actuating devices for one or another set being operated from a keyboard according to the magazine from which it is desired to deliver matrices, whereby matrices may be drawn from one or another of the magazines, as desired, and assembled to form composed matrix lines.

Different means have been previously proposed for bringing the keyboard into operative relation with one or another of the magazines, as by shifting a set of operating members actuated by the keyboard into position to operate one or another of the sets of escapement actuating devices for the different magazines, but such means, as heretofore proposed, required the manipulation of devices separate from the keyboard or the provision of special shifting mechanism auxiliary to the keyboard mechanism.

The primary object of the present invention is to provide novel and improved means whereby operating members actuated by the keyboard may be brought automatically into position to operate the escapement actuating devices for one or another of the magazines, as desired, by the usual or already existing mechanism of the keyboard, and a further object is to so construct and arrange such means whereby the same may be controlled by certain keys on the usual keyboard.

Such improved matrix releasing means for a plurality of magazines not only simplifies the construction and operation of the machine, but it also enables the operator to instantly effect shifting of the operating members from operative relation with the escapement actuating devices for one magazine to operative relation with those for another magazine without distraction of the operator's attention from the keyboard or, when the machine is provided with an automatic keyboard operating device the operation of which is controlled by a previously prepared tape having code punchings representing the respective characters on the keys of the keyboard, the use of certain keys already comprised within the group making up the keyboard, for the purpose

of effecting a shift of composition from one magazine to another, enables such automatic keyboard operating device to be readily adapted thereto since the code punchings already existing in such devices include punchings for the particular keyboard keys assigned to the shifting operation.

To these and other ends, the invention consists in certain improvements and combinations and arrangements of parts all as will be hereinafter described, the features of novelty being pointed out particularly in the claims at the end of the specification.

In the accompanying drawing:

Figure 1 is a side elevation, partly in section, of the keyboard and related matrix releasing mechanism of a typographical machine embodying the present invention;

Figure 2 is a top plan view of the keyboard as shown in Figure 1;

Figure 3 is a detailed perspective view, on an enlarged scale, showing portions of the sets of escapement actuating devices and the corresponding operating members therefor, and the means provided by the present invention for shifting the operating members into operating relation with one or another set of the escapement actuating devices; and

Figure 4 is a view similar to Figure 3 but showing the operating members shifted from the position shown in Figure 3.

Similar parts are designated by the same reference characters in the different figures.

The invention is shown in the present instance as applied to a machine embodying a single set of operating members cooperative directly with the keyboard at their lower ends and having means for swinging their upper ends into operating relation with one or another set of escapement actuating devices, such as shown for example in U. S. Patent No. 1,542,774, granted June 16, 1925, 1 and 2 representing upper and lower matrix magazines mounted in superposed relation in the machine and provided respectively with sets of escapements 3 and 4 for controlling the delivery of matrices therefrom, the matrices delivered from either of the magazines being received by a common assembler front 5 through which they pass to the point where they are assembled into lines in the usual and well-known manner. 6 and 7 represent sets of escapement actuating devices for the escapements 3 of the upper magazine and the escapements 4 of the lower magazine, respectively, these sets of escapement actuating devices being arranged in rows,

one in front of the other, and being supported by the relatively fixed guides 8 and 9 at their upper ends and a relatively fixed guide 10 at their lower ends, to reciprocate vertically and thereby actuate the respective escapements and thus effect the delivery of the matrices from the corresponding channels of the respective magazines, in the usual or well-known way. A set of operating members 11, in the form of vertically reciprocatory bars or slides, are mounted in a frame 12 so that they may reciprocate substantially vertically therein, and the frame 12 is pivoted at its lower end or substantially at 13, to rock on the keyboard frame 14 so that the upper ends of the operating members 11 may swing forwardly and rearwardly and into register or operating relation with either of the sets of escapement actuating devices 6 and 7, it being understood that the operating members 11 are arranged in a row and are spaced so that their upper ends will be in positions to abut directly against the lower ends of the escapement actuating devices of the respective sets 6 and 7 when the operating members are swung into position beneath them.

The keyboard may be of the usual and well-known construction, substantially as shown and described for example in U. S. Patent No. 1,153,078, granted September 7, 1915, it comprising the relatively fixed frame 14 in which a pair of continuously revoluble cam rollers 15 are mounted, a set of cam yokes 16 pivotally mounted above each cam roller and supporting a rotatable cam 17 above it, each cam yoke being normally supported in lifted position with its respective cam 17 out of contact with the cam roller by a pivoted trigger 18, and each trigger being connected to a vertically movable key bar 19, which is operatively connected to the appropriate key lever 20, the key levers being provided at their forward ends with finger keys 21 arranged usually in the manner shown in Figure 2. In such a keyboard, actuation of a key lifts the respective key bar 19, thereby rocking the respective trigger 15 into a position to release the respective cam yoke 16 and allow the cam thereon to drop into contact with the respective cam roller 15, and since the cam roller is power driven, the cam 17 will be driven thereby and its shape is such that it will lift the cam yoke 16 carrying it, and the cam yoke will lift or force upwardly the respective operating member 11, the lower end of which rests on the free end of the cam yoke. Since each of the operating members 11 is provided with a cam and cam yoke on which it rests, and each of these cam yokes operates in response to the actuation or depression of a key on the keyboard, the set of members 11 constitute power operated devices controlled by the keys of the keyboard.

According to the present invention, certain keys of the keyboard, such as those marked "U" and "L", which are comprised within the group of the usual ninety character keys of the keyboard, are employed for effecting shifting of the swinging frame 12 to carry the operating members 11 therein into operating relation with the set 6 or the set 7 of escapement actuating devices for the upper and lower magazines respectively. The cams and cam yokes for these keys are included among those already existing in the keyboard mechanism, but the operating rods or members 11^a and 11^b corresponding to these particular keys, are arranged to act upon cams 22 and 23 respectively when such members are lifted or

actuated by the keyboard mechanism. These cams are fixed to the relatively stationary guide 10 for the lower ends of the escapement actuating devices 6 and 7, and they have inclined cam surfaces 22^a and 23^a respectively on their under sides, these cam surfaces of the cams being inclined in relatively reverse directions and extending transversely of the rows of escapement actuating devices 6 and 7. The upper ends of the operating members 11^a and 11^b which are arranged to cooperate with the respective inclined cam surfaces, are preferably correspondingly inclined or beveled at their upper ends, as at 11^c and 11^d respectively. While the members 11^a and 11^b are in their normal or lowered positions, the upper end of one of these members will rest against or closely adjacent to its respective cam while the upper end of the other operating member will be separated laterally from its cam, Figure 3 for example showing the upper end of the operating member 11^b closely adjacent to its cam 23 and the upper end of the operating member 11^a separated laterally from its cam 22, the set of operating members 11 being then in operating relation with one of the sets of escapement actuating devices as for example the set 6 in Figure 3, and the set of operating members 11 will remain in operating relation with the set of actuating devices 6 until the key marked "L" of the keyboard is depressed or actuated, which will cause the member 11^b to be lifted by its cam and cam yoke, the consequent upward thrust of this member against the inclined or beveled cam surface 23^a on the cam 23 supported on the stationary guide 10 causing the member 11^b to be deflected rearwardly, and since the member 11^b is guided in the frame 12 and the row of operating members 11 are also guided in this frame, the operating members 11 will be shifted rearwardly from operating relation with the set of escapement actuating devices 6 into operating relation with the set of escapement actuated devices 7, the parts as thus shifted being shown in Figure 4, and upon the descent or return motion of the operating member 11^b to normal position, a space will be left between its upper end and the inclined or cam surface of the cam 23, the upper end of the operating member 11^a then occupying a position closely adjacent to the inclined or cam surface of its cam 22, and the parts will occupy this position, with the operating members 11 in operating relation with the set of escapement actuating devices 7 for the lower magazine until the key "U" of the keyboard is depressed whereupon the cam and cam yoke for the member 11^a will be set into operation to lift or force the member 11^a upwardly, thereby forcing its upper end against the inclined or cam surface on the cam 22, the resulting deflection of the member 11^a forwardly swinging the frame 12 and the set of operating members 11 therein forwardly and removing said operating members from operating relation with the set of escapement actuating devices 7 and bringing them into operating relation with the set of escapement actuating devices 6 for the upper magazine.

Any suitable means may be provided for retaining the frame 12 in its respective shifted positions, such, for example, as a bracket 24 fixed to the stationary guide 10 and having a smooth face extending at a right angle forwardly therefrom, and an arm 25 fixed to the swinging frame 12 and having a friction pad 26 of leather or the like to contact with the face of the bracket 24.

with sufficient friction to retain the frame 12 in either of its shifted positions.

It will be seen from the foregoing that the present invention enables the usual operating members for the escapement actuating devices to be conveniently arranged to perform a shifting of the set of operating members into operating relation with the escapement actuating devices of one or the other of the magazines, by a simple manipulation of the key, actuation of the key marked "U" for example automatically effecting the swinging of the operating members into operating relation with the set of escapement actuating devices 6 for the upper magazine 1 so that the keyboard may effect the delivery of matrices therefrom and actuation of the key marked "L" will effect a reverse shift of the set of operating members and will bring them into operating relation with the escapement actuating devices 7 for the lower magazine 2 so that the keyboard may effect the delivery of matrices from that magazine. In each case, the swinging of the operating members back and forth from one operative position to the other is accomplished automatically through manipulation of the existing keys of the keyboard and the power driven actuating devices corresponding thereto and to the respective operating members, and each shift of the operating members directly renders effective the means for causing a shift in the reverse direction, the member 11^b being in a position to act on the cam 23 after the operating members have been brought to the position shown in Figure 3 by actuation of the member 11^a to shift the operating members in the reverse direction and bring them into the position shown in Figure 4, and the member 11^a then being in a position to act on the cam 22, after the member 11^b has descended to its normal position, to return the operating members to the position shown in Figure 3. Since the operating members 11^a and 11^b employed for shifting the operating members 11 into one or the other operating position may be in all respects like the operating members 11, except for their bevelled upper ends, and the members 11^a and 11^b will be operated by their respective cams and cam yokes like those for the operating members 11 and will be controlled by particular keys of the group comprising the usual keyboard, the invention may be readily applied to machines of the usual construction without requiring deviation from the usual standard keyboard arrangement, with the advantages hereinbefore noted, and the necessity of providing auxiliary or special shifting mechanism is avoided.

I claim as my invention:—

1. In a typographical machine having a plurality of matrix magazines each provided with a set of escapements, a set of actuating devices for each set of escapements, a set of finger keys, and a set of power driven devices responsive to actuation of said keys, one or another of said sets of escapement actuating devices being operative by said power driven devices, means cooperative with certain of said power driven devices to cause the operating movement of the latter to shift the remainder of the set of power driven devices to and fro, into and out of operating relation with the respective sets of escapement actuating devices.

2. In a typographical machine having a plurality of matrix magazines each provided with a set of escapements, a set of actuating devices for each set of escapements, a set of finger keys, and a set of power driven operating members re-

sponsive to actuation of said keys and shiftable into operating relation with one or another of said sets of escapement actuating devices, means cooperative with certain of said power driven members to cause the operating movement of said members to shift the remainder of the set of power driven members into operating relation with one or another of said sets of escapement actuating devices.

3. In a typographical machine having a plurality of matrix magazines each provided with a set of escapements, a set of actuating devices for each set of escapements, a set of finger keys, and a set of power driven members responsive to actuation of said keys, means cooperative with certain of said power driven members to cause the operating movement of said members to shift the remainder of the set of said members into operating relation with one or another of said sets of escapement actuating devices.

4. In a typographical machine having a plurality of matrix magazines each provided with a set of escapements, a set of actuating devices for each set of escapements, a set of finger keys, and a set of power driven members responsive to actuation of said keys, means cooperative with certain of said power driven members to cause the operating movement of said members to respectively shift the entire set of said members into different positions and thereby bring the remainder of said members into operating relation with one or another of said sets of escapement actuating devices.

5. In a typographical machine having a plurality of matrix magazines each provided with a set of escapements, a set of actuating devices for each set of escapements, a set of finger keys, and a set of power driven members responsive to actuation of said keys, relatively reversed cams cooperative with certain of said power driven members for respectively shifting the entire set of said members into one or another position and thereby bring the remainder of said members into operating relation with one or another of said sets of escapement actuating devices.

6. In a typographical machine having a pair of matrix magazines each provided with a set of escapements, a set of actuating devices for each set of escapements, said sets of actuating devices being mounted in two parallel rows, a set of finger keys, a set of reciprocatory power driven members responsive to actuation of said keys, and a frame supporting said members in a row and movable to carry said members into operating relation with one or the other set of escapement actuating devices, a pair of cams having relatively reverse inclines thereon extending transversely of said rows of escapement actuating devices and arranged opposite to a pair of power driven members to be respectively engaged thereby when operated to move said frame in one or the other direction and thereby bring the remainder of the set of power driven members into operating relation with one or the other set of escapement actuating devices.

7. In a typographical machine having a pair of matrix magazines each provided with a set of escapements, a set of actuating devices for each set of escapements, a set of finger keys, and a corresponding set of power driven members responsive to the actuation of said keys, means cooperative with certain of said power driven members upon actuation of the latter in response to their corresponding finger keys to effect shifting of the entire set of said members alternately in opposite directions and thereby bring them

- into operating relation with one or the other set of escapement actuating devices.
8. In a typographical machine having a pair of matrix magazines each provided with a set of escapements, a set of actuating devices for each set of escapements, a set of finger keys, and a set of power driven members responsive to the actuation of said keys and shiftable in opposite directions into operating relation with one or the other set of escapement actuating devices, means upon which one of said members is operative when actuated in response to its key to effect shifting of the entire set of said members in one direction and to concurrently render another of said members operative upon said means to shift the entire set of said members in the opposite direction when actuated in response to another key.
9. In a typographical machine having a plurality of matrix magazines each provided with a set of escapements, a set of actuating devices for each set of escapements, a set of finger keys, a set of power driven devices responsive to actuation of said keys, one or another of said sets of escapement actuating devices being operative by said power driven devices, and shift control means cooperative with certain of said power driven devices, movement imparted to the power driven devices cooperative with said shift control means in response to actuation of their corresponding keys being operative to shift the remainder of the set of power driven devices alternately in opposite directions into and out of operating relation with one or another set of escapement actuating devices.
10. In a typographical machine having a plurality of matrix magazines each provided with a set of escapements, a set of actuating devices for each set of escapements, a set of finger keys, a set of power driven devices responsive to actuation of said keys, one or another of said sets of escapement actuating devices being operative by said power driven devices, and shift control means cooperative with certain of said power driven devices, movement imparted to the power driven devices cooperative with said shift control means in response to actuation of their corresponding keys being operative to shift the remainder of the set of power driven devices alternately in opposite directions into and out of operating relation with one or another set of escapement actuating devices.
11. In a typographical machine having a plurality of matrix magazines each provided with a set of escapements, a set of actuating devices for each set of escapements, a set of finger keys, a set of power driven devices responsive to actuation of said keys, one or another of said sets of escapement actuating devices being operative by said power driven devices, and shift control means in the path of movement of certain of said power driven devices, movement imparted to the power driven devices cooperative with said shift control means, in response to actuation of their keys, being operative through cooperation with said means to cause the entire set of power driven devices to shift to and fro in respect to the respective sets of escapement actuating devices.
12. In a typographical machine having a plurality of matrix magazines each provided with a set of escapements, a set of actuating devices for each set of escapements, a set of finger keys, a set of power driven devices responsive to actuation of said keys, one or another of said sets of escapement actuating devices being operative by said power driven devices, and a member cooperative with one of said power driven devices, movement imparted to the power driven device with which said member is cooperative, in response to actuation of its key, being opposed by said cooperating member and operative to shift the power driven device laterally and to cause the remainder of the power driven devices to correspondingly shift from operating relation with one set of escapement actuating devices to operating relation with another set of such devices.

HERMAN R. FREUND.
